UNITED STATES PATENT OFFICE.

JOHN D. E. DUNCAN, OF EAST ORANGE, NEW JERSEY; LENA ELIZABETH HILL DUNCAN
EXECUTRIX OF SAID JOHN D. E. DUNCAN, DECEASED.

INSULATOR.

1,128,424.

Specification of Letters Patent.

Patented Feb. 16, 1915.

Continuation in part of application Serial No. 391,893, filed September 9, 1907. This application filed January 2, 1908. Serial No. 408,882.

To all whom it may concern:

Be it known that I, JOHN D. E. DUNCAN, a citizen of the United States, now residing at East Orange, in the county of Essex and 5 State of New Jersey, have invented certain new and useful Improvements Relating to Insulators, of which the following is a specification, taken in connection with the accompanying drawing, which shows an illustrative embodiment of the invention in elevation, parts being indicated in section.

This application comprises subject-matter disclosed in my copending patent application 391,893, filed September 9, 1907, which 15 matured on February 25, 1908 into Patent 880,203 of which this application is a continuation in part.

This invention relates to insulators and relates especially to high potential insulators such as are adapted for use on power 20 transmission lines where a number of compound insulators may be used in series and so connected together as to be sufficiently rigid to resist torsion and compression 25 strains as well as tension. Each insulator of the series may be composed of a number of nested portions or domes having attached petticoats, the thickness of the inner nested portions being made less than that of the 30 outer ones to properly reduce the potential on the opposite faces of the inner elements due to condenser action and the various elements and compound insulators being self-protecting so that even under extreme conditions 35 excessive potential will cause flashing or arcing around them instead of causing puncture or injury by excessive surface leakage.

In the illustrative embodiment of this invention shown in the drawing, each compound insulator may comprise an inner dome 79 having a substantially uniform thickness and provided with the integral depending petticoat 92. If desired for particularly high voltage service the inner petticoat and dome may be made of some material having higher specific resistance than the outer domes, especially high resistance material suitable for the inner dome being 45 for example glass, micanite or other highly insulating compound which may be molded directly upon the connector end. This inner element of the compound insulator may be nested within one or more other insulating

elements comprising domes and integral petticoats formed of porcelain or other insulating material and these elements may be so arranged as to be readily assembled by nesting them together, that is, by simply slipping the domes inside of one another, the 55 various elements being preferably so formed as to allow this method of assembly. As indicated, the intermediate dome 78 may have a substantially uniform thickness and be provided with the depending intermediate 60 petticoat 82 which may be slightly thinner adjacent its edge. The outer dome 85 of substantially uniform thickness may have the integral outer petticoat 72 of gradually decreasing thickness toward its edge and 65 these outer elements may be formed of porcelain as is also the case with the inner insulating element for some service.

The series of nested domes may be supported within a suitable body portion or 70 head 73 which may be provided with a suitable inclined supporting shoulder 83 adjacent its lower edge. The outer dome may be formed with a coöperating shoulder or series of projections 89 and may also be provided 75 on its inner face with the shoulder 86 with which the shoulder 87 on the intermediate dome coöperates, this intermediate dome having, if desired, a suitable inclined shoulder 95 on its inner face. The inner dome 85 may have similar projections or inclined shoulders 96, 97, the latter coöperating with the inclined or flaring portion 98 on the connector 71. The insulating elements having been first separately tested, if desired by subjecting them to potentials greater than required to flash or arc around the petticoats 90 under service conditions, may be assembled by nesting them together, that is, by slipping them one within another within the head or 95 body portion 73 and arranging the connector 71 properly within the inner dome. These parts may then be locked or rigidly secured together in proper position by the use of cement, (which may be made waterproof by 100 treatment with shellac, paraffin, etc.) pressure members or other suitable binding means which prevent the removal of the parts and is adapted to transmit tension strains angularly outward through the coöperating shoulders so as to give the compound insulator a 105 much greater strength in resisting tension. Any desired number of similar compound

insulators may be mounted in the series in any desired way by securing together the metallic members thereof, that is, the heads and connectors, for example by screwing or otherwise securing the lower end of the connector 71 into the head 66 of the insulator below. The metallic portion of the insulator at one end of the series may be supported in any desired way and the other 10 terminal metallic member may be secured to a wire or other conductor by any suitable means. As indicated in the drawing, the connector 64 of the lower insulator may be mounted in a suitable support 62 so as to be 15 rigidly supported from the base 61 while the conductor 81 may be secured to the head 73 of the top insulator as by the use of the yoke 80 bolted down upon it.

Under normal dry weather conditions, the 20 cement or other binding means locking the elements of the compound insulator together acts somewhat as the conducting element of a condenser, so that each nested dome of the insulator between the layers of cement, etc., 25 is probably subjected to about the same proportion of the total potential on the compound insulator as is determined by the constants of these different condensers acting in series. Considering, for simplicity a two- 30 part compound insulator in which the domes are of the same material and thickness the inner dome because of its relatively smaller surface in contact with the cement so as to have condenser action has a considerably less 35 capacity as a condenser as compared to the outer dome. Since in a series condenser alternating circuit the potential across each condenser is inversely proportional to its capacity, the inner dome having a smaller 40 capacity is for generally similar reasons thus subjected to a greater potential which cannot be so well taken care of and may lead to its puncture or failure. The capacity of the inner dome as a condenser may, however, be 45 increased by making thinner the porcelain or other insulating dielectric of this insulator dome which apparently seems to increase the capacity and thus relieve the working potential on this dome to a greater extent than the 50 insulating action of the dome is reduced by its decreased thickness. Or, to put the matter in a little different way, the inner dome may with advantage be made of such thickness and proportions as to safely withstand 55 the normal potential to which it is subjected by this condenser action and the outer dome or domes in which it is nested are made proportionately thicker so as to insure against the inner dome being subjected to an excessive 60 proportion of the total potential on the insulator because of the condenser effects referred to. By making the inner dome of some such compound insulator as is illustrated in the drawing of considerably less 65 thickness the potential thus exerted upon its

opposite faces that is, the condenser potential, is materially reduced and a much more desirable distribution of condenser potential on the various domes is secured if the inner ones are made considerably thinner than those outside them; in some cases it may be desirable to make the nested domes of a uniform thickness substantially proportional to their mean diameter. By making the inner domes sufficiently thinner than the outer ones, the condenser potential upon them may be reduced and also the brush discharge between the opposite faces of adjacent petticoats near the domes may be materially decreased and practically eliminated in some 80 cases.

The length of the inner petticoats is made considerably less than the length of the outer ones so as to limit the potential that can be maintained on the opposite faces of 85 the dome by allowing leakage over the surface of the petticoat. The inner petticoat 92, for instance, must, in order to properly limit the potential on the inner dome, be made very much shorter than the intermediate petticoat because having a less width of leakage path. Under wet weather conditions the outer surface of the outer petticoat of the compound insulator becomes wet and also under some conditions considerable 95 condensation moisture collects on the other parts of the petticoats so as to materially decrease the resistance to surface leakage. The petticoats may be made sufficiently flaring so that the angle between the coöperating 100 faces of adjacent petticoats is such that the striking or arcing potential between two opposite points on adjacent petticoats is less than is required to leak along the surface between these two points, so 105 that undue surface leakage and heating of the parts is thereby prevented.

The several compound insulators may be so mounted that the striking or arcing potential between the edge of the outer petticoat 72 and the head 66 of the insulator below is less than is required to leak along the surfaces of the various petticoats interposed between. The distance over the various petticoats comprising each insulator is 115 thus made sufficiently great so that undesirable surface leakage will not take place at any potential that can be maintained before direct arcing from the edge of the outer petticoat to the next compound insulator below 120 takes place. This direct arcing which acts to relieve the potential and prevent undesirable surface leakage may be promoted if desired by the interposition of suitable arcing members which may be supported on 125 the petticoats or preferably on portions of the compound insulators. As indicated, the arcing member 68 may be removably mounted on the head 66 by slipping the spring clip 130 on this arcing member into the groove 67

formed in the head, the resilience of the two parts of this arcing member held together by the rivets 69 securely holding the member in position. Suitable tips 70 and 91 are 5 formed on this arcing member, preferably considerably outside of the petticoats and in position to coöperate with the similar tip 93 on the arcing member 76 which may be similarly mounted in a groove 75 in the 10 head 73. If desired another arcing member 63 may be mounted on the support 62 and have a tip 90, these tips or arcing portions 15 of the arcing members being as indicated preferably located considerably outside of the line of the petticoats, that is, farther 20 away from the axis of the insulators so as to draw and keep away from the petticoats any arc that may be formed.

Under extreme service conditions, varying 25 condensation or collection of dust on the insulators may cause a very excessive voltage to be thrown on one or more petticoats or compound insulators. For this reason, it is highly important to have the various insulators and their component insulating elements self-protecting so that even under these extreme conditions the excessive potential will cause flashing or arcing around them instead of either puncturing or injuring them by excess surface leakage. Each 30 of the petticoats may be made sufficiently short and the compound insulators may be placed close enough together to make them self-protecting and to allow such arcing to 35 take place without damage and in sufficient amount to substantially equalize the potential carried by the various compound insulators and their elements. Such arcing naturally tends to quickly dry off the surface 40 of the insulator or burn off dust collected upon it so as to bring up the impaired resistance of any element and restore the normal distribution of potential throughout the 45 system.

Having described this invention in connection with illustrative materials, proportions and embodiments, to the details of which disclosure the invention is not, of course, to be limited, what is claimed as new 50 and what is desired to be secured by Letters Patent is set forth in the appended claims.

1. In insulators, a plurality of compound insulators, connectors substantially rigidly securing said insulators together, each of 55 said insulators comprising a body portion, more than two nested domes within said body portion and provided with integral flaring petticoats, said inner domes having shoulders coöoperating with enlarged portions on said connectors, binding material locking the parts of said compound insulators together, each of said domes being of substantially uniform thickness and the inner domes being of considerably less 60 thickness than the outer domes to reduce the

condenser potential on said inner domes, said inner petticoats being considerably shorter than said outer petticoats to limit the potential on said inner domes and promote the self-protecting action of the insulating elements, arcing members mounted 70 on said insulators and having tips extending out beyond the line of said petticoats to allow arcing away from said petticoats and promote the self-protecting action of said 75 compound insulators.

2. In insulators, a plurality of compound insulators mounted in series, each of said insulators comprising a body portion, a series of nested domes within said body portion and provided with integral petticoats, binding means holding the parts of said compound insulators together, each of said 80 domes being of substantially uniform thickness and the inner domes being of considerably less thickness than the outer domes to reduce the condenser potential on said inner domes, said inner petticoats being considerably shorter than the outer petticoats to 85 promote the self-protecting action of the insulating elements, said inner domes being formed of more highly resistant material than said outer domes, and means to allow direct arcing around one of said compound 90 insulators and away from the petticoats 95 thereof to promote the self-protecting action of said insulator.

3. In insulators, a plurality of compound insulators mounted in series, each of said insulators comprising a body portion, a series of petticoats and integral domes arranged one within another and held in position and arcing members attached to said insulators to allow direct arcing between them away from the petticoats of said insulators 100 to promote the self-protecting action of said insulators.

4. In insulators, a plurality of insulators mounted in series and arcing members mounted on the heads of said insulators to 105 allow arcing around said insulators out of substantial contact therewith to minimize arcing damage and thereby promote the self-protecting action of said insulators.

5. In insulators, a series of more than two 110 petticoats having integral domes arranged within one another, binding means to hold the parts of said insulator together, each of said domes being of substantially uniform thickness, said insulator comprising an 115 inner dome of considerably less thickness and formed of more highly resistant material than an outer dome and an inner petticoat considerably shorter than an outer petticoat to promote the self-protecting 120 action of the insulating elements.

6. The compound insulator comprising a body portion, a series of petticoats having integral domes arranged one inside another in said body portion, and protected and sub- 130

- stantially inclosed thereby, binding means to hold the parts of said insulator together, said insulator comprising an inner dome of considerably less thickness than an outer dome to limit the condenser potential on said inner dome, and an inner petticoat of considerably less length than an outer petticoat to promote the self-protecting action of the insulating elements.
- 10 7. The compound insulator comprising a series of petticoats and connected supporting domes arranged one inside another and means to hold the insulating elements in position, one of said inner domes being of substantially less thickness and formed of more highly resistant material than an outer dome.
- 15 8. The compound insulator comprising a plurality of insulating petticoats and attached imperforate insulating domes each of substantially uniform thickness and arranged one inside another and means to secure the insulating elements in position, the innermost of said insulating elements having a dome of considerably less thickness and having an attached petticoat of considerably less length and resultant surface leakage resistance than the adjacent outer insulating element to limit the condenser potential on said innermost dome and promote the self-protecting action of said insulating elements.
- 20 9. The compound insulator comprising a plurality of petticoats and attached domes arranged one inside another and means to hold the insulating elements in position, one of said inner domes being formed of more highly resistant material than one of said outer domes.
- 25 40 10. The compound insulator comprising a plurality of insulating petticoats and attached imperforate insulating domes arranged one inside another and means to secure the insulating elements in position, the innermost of said insulating elements having a dome of considerably less thickness and having an attached petticoat of considerably less length and resultant surface leakage resistance than the adjacent outer insulating element to limit the condenser potential on said innermost dome and promote the self-protecting action of said insulating elements.
- 30 55 11. The compound insulator comprising a plurality of insulating elements arranged one inside another, one of said inner insulating elements being considerably thinner and being formed of more highly resistant material than one of said outer elements.
- 60 12. An insulator comprising a plurality of nested domes provided with integral flaring petticoats and with a head within which said domes are mounted and an arcing member having a spring clip detachably mounting said arcing member on said head and
- having tips located beyond the line of said petticoats and extending toward the same.
- 65 13. An insulator comprising a petticoat and an arcing member mounted on said insulator and having a tip located beyond the line of said petticoat and extending toward the same.
- 70 14. The compound insulator comprising a body portion, a series of more than two petticoats and attached imperforate domes arranged one inside another in said body portion, each of said inner domes being of less thickness than the dome within which it is located to limit the condenser potential on said inner domes.
- 75 15. The compound insulator comprising a body portion and a series of more than two petticoats and attached imperforate domes arranged one inside another in said body portion, and binding means to hold the parts of said insulator in position, each of said domes being of less thickness than the dome within which it is located, and each of said petticoats offering less resistance to the passage of electricity around it than the petticoat within which it is located.
- 80 16. The compound insulator comprising a series of more than two petticoats and connected imperforate domes arranged one inside another, each of said inner petticoats having less resistance to the passage of electricity around it than the petticoat within which it is located.
- 85 17. The compound insulator comprising a body portion, a series of imperforate domes and integral petticoats nested within said body portion, binding means to hold the parts of said insulator in position, each of said domes being of less thickness than the dome within which it is located to reduce the condenser potential on said inner dome and each of said petticoats being considerably shorter and offering less resistance to the passage of electricity around it than the petticoat within which it is located to promote the self-protecting action of the insulating elements.
- 90 105 18. The compound insulator comprising a body portion, a series of imperforate domes nested within said body portion and provided with integral petticoats, binding means holding the parts of said compound insulator together, each of said domes being of substantially uniform thickness and each inner dome being of considerably less thickness than the dome outside thereof to reduce the condenser potential on said inner dome and the inner petticoat integral with said inner dome being considerably shorter than the petticoat outside thereof to promote the self-protecting action of the insulating elements.
- 110 115 120 125 19. In insulators, a plurality of compound insulators, connectors substantially rigidly securing said insulators together, each of
- 130

- said insulators comprising a body portion, more than two nested domes within said body portion and provided with integral flaring petticoats, said inner domes having shoulders coöperating with enlarged portions on said connectors, binding material locking the parts of said compound insulators together, each of said domes being of substantially uniform thickness and the inner domes being of considerably less thickness than the other domes to reduce the condenser potential on said inner domes and said inner petticoats being considerably shorter than said outer petticoats to limit the potential on said inner domes and promote the self-protecting action of the insulating elements.
20. In insulators, a plurality of compound insulators mounted in series, each of said insulators comprising a body portion, a series of imperforate domes nested within said body portion and provided with integral petticoats, binding means holding the parts of said compound insulators together, each of said domes being of substantially uniform thickness and the inner domes being of considerably less thickness than the outer domes to reduce the condenser potential on said inner domes, and said inner petticoats being considerably shorter than the outer petticoats to promote the self-protecting action of the insulating elements.
21. The compound insulator comprising a metallic body portion, a series of petticoats having integral domes arranged one inside another within said body portion and protected and substantially inclosed thereby, binding means rigidly holding the parts of said insulator together, said insulator comprising an inner dome of considerably less thickness than the outer domes, to limit the condenser potential on said inner dome and an inner petticoat of considerably less length than an outer petticoat to promote the self-protecting action of the insulating elements.
22. The compound insulator comprising a metallic body portion and a series of petticoats having attached imperforate domes arranged one inside another within said body portion and protected and substantially inclosed thereby, said insulator comprising an inner dome of considerably less thickness than an outer dome to limit the condenser potential on said inner dome and an inner petticoat having less resistance to the passage of electricity around the same than one of said outer petticoats to permit the self-protecting action of the insulating elements.
23. A compound insulator comprising a metallic body portion, a series of petticoats having integral domes arranged one inside another within said body portion and protected and substantially inclosed thereby,
- 5 and binding means to hold the parts of said insulator rigidly together, one of said inner petticoats having considerably less resistance to the passage of electricity around the same than one of said outer petticoats to 70 permit the self-protecting action of the insulating elements.
24. The compound insulator comprising a metallic body portion, a series of more than two petticoats and attached imperforate 75 domes arranged one inside another within said body portion and protected and substantially inclosed thereby, each of said inner domes being of less thickness than the dome within which it is located to limit the 80 condenser potential on said inner domes.
25. In insulators, a series of compound insulators provided with petticoats and attached nested imperforate domes and metallic body portions within which said domes 85 are supported and substantially inclosed and protected and connectors secured to said body portions and substantially rigidly securing said insulators together and holding them spaced apart in series and out of 90 interfering distance and a support connected to the lower insulator to support said substantially rigid connected series of insulators.
26. In insulators, a plurality of insulators 95 comprising metallic bodies and petticoats having connected imperforate domes located within said bodies, said bodies being provided with attaching grooves and arcing members having clips engaging said grooves 100 to rigidly support said arcing members from said heads, said arcing members being provided with approaching tips extending out considerably beyond the line of said petticoats to keep any arcs formed away 105 therefrom.
27. An insulator comprising a series of petticoats and attached imperforate domes, a metallic body within which said domes are located, said body being provided with an 110 annular groove and an arcing member having a spring clip engaging said groove and rigidly supporting said arcing member on said body, said arcing member being provided with a tip extending out considerably 115 beyond the line of said petticoats.
28. In insulators, a series of insulators comprising metallic bodies, insulating members secured to said bodies and comprising petticoats and arcing members secured to 120 said bodies and having coöperating tips extending out considerably beyond the line of said petticoats.
29. An insulator comprising a metallic body provided with an attaching depression, an insulating member provided with a petticoat secured to said body and an arcing member having means coöperating with said attaching depression to disengageably and rigidly mount said arcing member upon 125 130

said body and a tip on said arcing member extending out considerably beyond the line of said petticoat.

30. The compound insulator comprising a metallic body portion, a series of more than two petticoats and integral imperforate domes nested within said body portion, and protected and substantially inclosed thereby, binding means to hold the parts of said insulator in position, each of said domes having a substantially uniform thickness substantially proportional to its mean diameter to equably apportion the condenser potential on said domes and each of said petticoats offering less resistance to the passage of electricity around it than the petticoat within which it is located to promote the self-protecting action of the insulating elements. 50

31. The compound insulator comprising a metallic body portion, a series of more than two petticoats and integral imperforate domes nested within said body portion and protected and substantially inclosed thereby, binding means to hold the parts of said insulator in position, each of said domes having a substantially uniform thickness substantially proportional to its mean diameter to equably apportion the condenser potential on said domes. 60

30 32. The compound insulator comprising a series of more than two petticoats and integral imperforate domes, binding means to hold the parts of said insulator in position, each of said domes having an average thickness substantially proportional to its mean diameter to apportion the condenser potential on said domes. 65

33. The compound insulator comprising a metallic body portion, a series of petticoats and attached imperforate domes nested within said body portion and protected and substantially inclosed thereby, binding means holding the parts of said compound insulator together, each of said domes having a substantially uniform thickness substantially proportional to its mean diameter to apportion the condenser potential 75

45

to apportion the condenser potentials equably between the different domes and the inner petticoat integral with said inner dome offering less resistance to the passage of electricity around it than the petticoat outside thereof to promote the self-protecting action of the insulating elements. 80

34. The compound insulator comprising a series of petticoats and attached imperforate domes, binding means holding the parts of said compound insulator together, each of said domes having a substantially uniform thickness substantially proportional to its mean diameter to apportion the condenser potentials equably between the different domes and the inner petticoats integral with said inner dome offering less resistance to the passage of electricity around it than the petticoat outside thereof to promote the self-protecting action of the insulating elements. 85

35. The compound insulator comprising a series of petticoats and attached imperforate domes, binding means holding the parts of said compound insulator together, each of said domes having an average thickness substantially proportional to its mean diameter to apportion the condenser potentials equably between the different domes and the inner petticoat integral with said inner dome offering less resistance to the passage of electricity around it than the petticoat outside thereof to promote the self-protecting action of the insulating elements. 90

36. The compound insulator comprising a series of petticoats and attached imperforate domes, binding means holding the parts of said compound insulator together, each of said domes having an average thickness substantially proportional to its mean diameter to apportion the condenser potentials equally between the different domes. 85
